UNITED STATES PATENT OFFICE.

WALTER C. BECKWITH, OF FOSTORIA, OHIO.

HYDRAULIC STRAIN-EQUALIZER.

1,311,108.

Specification of Letters Patent. Patented July 22, 1919.

Application filed November 4, 1918. Serial No. 261,096.

To all whom it may concern:

Be it known that I, WALTER C. BECKWITH, citizen of the United States of America, residing at Fostoria, in the county of Seneca 5 and State of Ohio, have invented certain new and useful Improvements in Hydraulic Strain-Equalizers, of which the following is a specification.

The present invention relates to hydraulic 10 strain equalizers and has for its object to provide a simple and effective means for equalizing or relieving the strain on lifting and hauling cables or analogous flexible means.

15 Considerable difficulty has been experienced in raising sunken vessels due to the fact that the cables employed were incapable of withstanding the strain placed upon them, it frequently happening that where 20 one cable was subjected to a greater strain than the others, it would snap thus throwing an added weight upon the others with the result that they would all give away.

This is obviated by my invention.

25 Other and further objects will be in part described and in part obvious as the specification is proceeded with.

In the accompanying drawings forming part of this specification:

30 Figure 1 is a side view of a ship having my invention attached showing its use in connection with the salvaging of sunken vessels;

35 Fig. 2 is a section on the line 3—3 Fig. 3 showing the hoisting apparatus and connections;

Fig. 3 is a side view partly in section of my invention;

40 Fig. 4 is a modified form of my invention; and

Fig. 5 is a further modification thereof in sectional elevation.

Referring more particularly to the drawings in which like reference numerals refer 45 to corresponding parts throughout the several views, 1 denotes a ship mounted upon the deck 2 of which is a plurality of hollow castings or base plates 3 suitably secured to the deck by bolts or other fastenings 4.

50 Each end of the castings 3 is formed with a cylinder 5 having its lower end opening into the chamber 6 in the castings and closed at its upper end by threaded caps 7. Pistons 8 carried by stems 9, passing through the

55 caps 7 operate in the cylinders, the upper ends of the stems carrying pulleys 10 axially

aligned therewith for a purpose to be described hereinafter.

Preferably centrally disposed between each pair of cylinders 5 is a cylinder 11 projecting upwardly from and formed integral with the casting 3. These cylinders 11 have restricted openings 12 at their lower ends communicating with the chamber 6 and at their upper ends are closed by threaded caps 13 similar to the caps 7. Stems 14 having angled ends 15 pass through the caps 13 and carry at their lower ends what may be termed auxiliary pistons 16, the latter being normally seated to close the openings 12 by means of coil springs 17 bearing at opposite ends against the cap 13 and piston 16 respectively. The tension of these springs may be readily adjusted by screwing up or unscrewing the caps 13 as desired. 60 65 70 75

When the chamber 6 is filled with a suitable liquid, preferably heavy oil, and the cylinders 5 and 11 partially filled as indicated in Fig. 2, any downward pressure upon the stems 9 tends to force the piston 16 and its stem upwardly in an obvious manner. This upward movement of the piston 16 is resisted by the spring 17 which is of sufficient strength to overcome a predetermined pressure of say twenty five tons. 80 85

In the embodiment of the invention illustrated I have shown its application to the art of raising sunken vessels. In Figs. 1 and 3, 18 are cables which pass over the pulleys 10 on the piston stems 9 and are connected at one end as at 19 to the vessel 20 to be raised and at the other end to the drum 21 of a hoisting apparatus 22. The drum 21 may be manually operated by means of gears 23—24 and crank handle 25 90 95 for the purpose of drawing the cables taut, but the lifting operation is effected by any suitable power plant such as a steam, electric or gasoline motor 26. As the hoisting apparatus and power driving means and connections may be of any approved type further detailed description thereof is deemed unnecessary. It will of course be understood that there will be as many power plants as base plates or units 3. 100 105

When either of the cables 18 of any pair is placed under a greater strain than twenty five tons the stem 9 and piston supporting the cable will be correspondingly depressed and automatically relieved by its companion cable due to a corresponding elevation of the piston and stem supporting the said 110

companion cable until such time as both cables come under the maximum strain of twenty five (25) tons. When a maximum strain of twenty five (25) tons is placed on 5 both cables the pressure exerted by the fluid against the bottom of piston 16 elevates the latter and shuts off the power plant and consequently stops the winding drum 21 whereupon the lifting operation is halted and all 10 strain on the cables 18 relieved in the following manner.

Each cylinder 11 is provided with a strap 27 encircling the same which supports a bell crank lever 28 one arm of which is 15 connected by a link 29 to the angular end 15 of the stem 14 while the other arm of the bell-crank is connected by a rod 30 to a lever 31 in turn adapted to stop and start the power plant 26 through the medium of a 20 valve or switch (not shown).

Disconnection of the power plant is effected through the mechanism just described by the elevation of the piston 16 and its stem 14 while the lowering of the piston 16 and 25 its stem, operates the valve or switch (not shown) to start the motor and the winding drum.

In the modification illustrated in Fig. 4 I employ a solid base plate 32 secured to the 30 deck 2 of the ship 1 by means of bolts 4. The plate 32 supports or has cast therewith a horizontally disposed cylinder 33 closed at one end by a threaded cap 34 through which extends a piston rod 35 carrying at one end 35 a piston 36. The opposite end of the rod or stem carries a pulley 37 and is pivoted to a bracket 38 slidably mounted in a plate 39 secured to the base plate 32 by bolts 40. It will be understood that the cylinder 33 contains 40 a heavy fluid such as oil 45.

The cylinder 33 is formed with a small tubular extension or neck 41 communicating at its inner end with the interior of the cylinder and closed at its outer end by a 45 threaded plug or closure member 42. A piston stem 43 carrying a piston 44 extends through the cap and connects at its outer end with the rod 30 leading to the power plant 26. A coil spring 46 bears at opposite ends against the closure member 42 and the piston 44 and normally tends to maintain the piston 44 in the position illustrated in the drawing. The operation is as follows:

The tension of spring 46 is regulated 55 by means of the screw plug or closure 42 to overcome a pressure of say twenty five (25) tons and when the pressure exerted by the cable 18 passing over drum 21, pulley 37 and idler pulley 47 60 exceeds twenty five (25) tons the piston 36 is forced in the direction of the arrow, the pulley 37 and sliding bracket 38 of course moving simultaneously therewith. This movement of the piston 36 causes the 65 piston 44 to overcome the tension of the

spring 46 and to move with its stem 43 in the direction of the arrow. This movement of the stem 43 is communicated through the rod 30 to the lever 31 thus stopping the power plant and the winding drum 21 and 70 thereby relieving the pressure on the cable 18. As soon as the pressure drops below twenty five (25) tons the movement of parts just described will be reversed and the power plant will be automatically started and the 75 lifting operation will continue.

The modification shown in Fig. 5 comprises a base 48 adapted to be secured to the deck of a ship by bolts or the like 49. A pair of vertically disposed cylinders 50 and 80 51 cast integrally with the base 48 are connected at their lower ends by a valved pipe 52. The upper ends of the cylinders are closed by a cap 53 and screw plug 54 respectively. The cylinder 50 is partly filled 85 with heavy oil and contains a piston 55 the stem 56 of which projects through the cap 53 and carries a pulley 10 similar to that shown in Figs. 1, 2 and 3. A piston 57 operating in the cylinder 51 has a stem 58 90 passing through the plug 54 provided with an angular end similar to the end 15 of the piston 14 Figs. 1, 2 and 3. This angular end of the stem 58 is connected to the power plant in the identical manner illustrated in 95 the preferred embodiment of my invention. A coil spring 59 surrounds the stem 58 and bears at opposite ends against the plug 54 and piston 57 normally holding the latter in the lowermost position illustrated. 100

In practice the tension of coil spring 59 is adjusted by means of the plug 54 to overcome a pressure of twenty five tons exerted against the bottom of piston 57 when the valve 60 has been opened a predetermined 105 distance.

When the cable 18 is put under a strain exceeding that of twenty five (25) tons the stem 56 and piston 55 will be depressed, thus forcing the oil in cylinder 50 and pipe 110 52 through the latter against the bottom of piston 56 elevating the latter and effecting the stopping of the winding drum in the manner herein described.

Having thus described my invention, what 115 I claim is:

1. A device of the type described, including opposed pistons, cables controlled by said pistons for lifting heavy bodies, an auxiliary piston, means providing communication between the containing chambers of said pistons, said chambers being supplied with a liquid, resilient means provided within the auxiliary piston-chamber for opposing the pressure of fluid on said auxiliary piston, and means controlled by said auxiliary piston for limiting the pull which the hoisting means may exert upon any given set of cables. 120

2. A device of the type described, includ- 125

ing hydraulic pistons, cables controlled by said pistons for lifting heavy bodies, an auxiliary hydraulic piston, means providing communication between the containing 5 chambers of said pistons, said chambers being supplied with a liquid, resilient means provided within the auxiliary piston-chamber for opposing the pressure of fluid on said auxiliary piston, and means controlled by 10 said auxiliary piston for limiting the pull which the hoisting means may exert upon any given set of cables, comprising an automatic cut off and connections between the same and the auxiliary piston.

15 3. A device of the type described, including opposed hydraulic pistons, cables controlled by said pistons for lifting heavy bodies, the rods of said pistons being equipped with rotary members over which 20 are passed said cables, an auxiliary hydraulic piston, means providing communication between the containing chambers of said pistons, said chambers being supplied with a liquid, resilient means provided with 25 in the auxiliary piston-chamber for opposing the pressure of fluid on said auxiliary piston and means controlled by said auxiliary piston for limiting the pull which the hoisting means may exert upon any 30 given set of cables.

4. A device of the type described, includ-

ing opposed pistons, cables controlled by said pistons for lifting heavy bodies, an auxiliary piston, a base member affording communication between the containing 35 chambers of said pistons, said piston-containing chambers and said base-member providing for containing the piston-compressed liquid, resilient means provided within the auxiliary piston chamber for 40 opposing the pressure of fluid on said auxiliary piston and means controlled by said auxiliary piston for limiting the pull which the hoisting means may exert upon any given set of cables. 45

5. A device of the type described, including a piston, a cable controlled by said piston for hoisting heavy bodies, an auxiliary piston, means providing communication between the containing chambers of said pistons, a body of liquid being provided intermediate of, and in contact with said pistons, and automatically controlled means controlled by said auxiliary piston for limiting the pull which may be exerted on the 50 hoisting cable. 55

In testimony whereof I affix my signature in presence of two witnesses.
